SPOON OR SIMILAR ARTICLE

Donald A. Wallace, Croton-on-Hudson, N. Y.

Application January 14, 1953, Serial No. 23,125

Term of patent 14 years

(Cl. D44—29)

To all whom it may concern:

Be it known that I, Donald A. Wallace, a citizen of the United States, residing at Croton-on-Hudson, in the county of Westchester and State of New York, have invented a new, original, and ornamental Design for a Spoon or Similar Article, of which the following is a specification, reference being had to the accompanying drawing, forming part thereof.

In the drawing:

Fig. 1 is a top plan view of a spoon or similar article, showing my new design;

Fig. 2 is a side elevational view thereof;

Fig. 3 is a cross sectional view taken on the line 3—3 of Fig. 2;

Fig. 4 is a cross sectional view taken on the line 4—4 of Fig. 2;

Fig. 5 is a cross sectional view taken on the line 5—5 of Fig. 2;

Fig. 6 is a cross sectional view taken on the line 6—6 of Fig. 2;

Fig. 7 is a cross sectional view taken on the line 7—7 of Fig. 2; and

Fig. 8 is a cross sectional view taken on the line 8—8 of Fig. 2; and

Fig. 9 is a cross sectional view taken on the line 9—9 of Fig. 2.

Fig. 10 is a perspective view of that shown in Fig. 1.

I claim:

The ornamental design for a spoon or similar article, as shown.
